UNITED STATES PATENT OFFICE.

LEWIS NIXON, OF NEW YORK, N. Y.

INCENDIARY PROJECTILE.

1,153,513.

Specification of Letters Patent. Patented Sept. 14, 1915.

Application filed November 25, 1914. Serial No. 874,001.

To all whom it may concern:

Be it known that I, LEWIS NIXON, a citizen of the United States, residing at New York, in the county of New York and State of New York, have invented certain new and useful Improvements in Incendiary Projectiles; and I do hereby declare the following to be a full, clear, and exact description of the invention, such as will enable others skilled in the art to which it appertains to make and use the same.

My present invention relates to improvements in incendiary projectiles intended to more especially set fire to balloons, Zeppelins, or other air craft, and is also intended for incendiary purposes in bombarding cities, fortifications, ships, or other objects composed wholly or in part of combustible materials.

According to my invention I use shrapnel of any ordinary or suitable design, in which, instead of metal balls, I use pellets or balls of a mixture similar to that known as "Greek fire," which balls are packed in a mixture of treated iron filings and special slow burning powder. A suitable fuse or bursting charge is supplied to burst the shrapnel and scatter the combustible products thereof.

My invention may be applied to any type of shrapnel, one type of which is shown in the accompanying drawing, which represents the ordinary United States service three-inch shrapnel; but which, instead of containing sulfur with lead balls, contains the combustible compound hereinbefore described. This drawing shows the shrapnel in central longitudinal section, with the fuse in elevation.

A represents the shell of the shrapnel, B the head which is screwed into the shell which is provided with a chamber B° for the bursting charge, which is preferably of black powder.

C represents the fuse which may be of any suitable type.

D represents the binder, made up of treated iron filings and special powder, and also the balls E of combustible material.

By having the bursting charge in front of the combustible material contained in the shell, there is a tendency to arrest, in a measure, the forward movement of the combustible mass and to disintegrate and scat-

ter the parts thereof while in the burning condition, thus causing said parts to more readily scatter, or drop downward, instead of continuing their onward movement. If desired, however, the bursting charge may be inserted in the rear or center of the combustible material; such forms of shrapnel being also well known in the art. Shrapnel of the usual exterior shape are preferred so that they may be used with guns of existing types, and may be packed in the usual containers for such ammunition.

Even a number of holes through the planes of an aeroplane made by shrapnel bullets or pieces of shell as now used are not necessarily fatal. But if one of a stream of these pellets, burning with fierce flame and intense heat, strike an aeroplane or dirigible, there is little likelihood of escape, as these fiery masses burn with a flame that neither rapid motion nor water will extinguish. One such flame on the planes of an aeroplane, or the envelop of a dirigible, would cause a rapidly extending hole that would quickly bring about the loss of the air craft.

While especially designed for destroying air craft, they can be most effectively used against men in intrenchments, or to set fire to buildings, or other inflammable objects.

The filling and pellets when burning give off bright light and render the shrapnel specially useful as range indicating means at night.

It will be obvious that various modifications might be made in the herein described device, which could be used without departing from the spirit of my invention.

Having thus described my invention what I claim and desire to secure by Letters Patent of the United States is:—

1. A projectile of the character described, comprising a metal casing containing a mass of highly combustible balls bound together with a combustible binder, a cap closing one end of said casing and provided with a chamber containing a bursting charge for bursting said casing and to scatter said inflammable material, and a fuse carried by said cap and adapted to ignite said bursting charge, substantially as described.

2. A projectile of the character described, comprising a metal casing containing a mass of highly combustible balls bound together

2
with a combustible binder, a cap closing the front end of said casing and provided with a chamber containing a bursting charge for bursting said casing and to scatter said inflammable material, and a fuse closing the front end of said cap and adapted to ignite said bursting charge.

In testimony whereof, I affix my signature, in presence of two witnesses.

LEWIS NIXON.
